(57) **CLAIM**

(51) **LOC (8) Cl.** **24-01**

The ornamental design for a controller for X-RAY apparatus for medical treatment, as shown and described.

(52) **U.S. Cl.** **D24/158**

DESCRIPTION

(58) **Field of Classification Search** D24/158-161,

FIG. 1 is a front, bottom and left side perspective view of a controller for X-RAY apparatus for medical treatment, showing my new design;

D24/183; 378/178-190, 193, 195-198, 208,
378/209, 10, 11, 37-39; D14/392-394, 396,
D14/397, 400, 412; D21/325, 331, 332

FIG. 2 is a front elevational view thereof;

See application file for complete search history.

FIG. 3 is a rear elevational view thereof;
